CAKE PLATE

Richard F. Reifers, New Canaan, Conn., and George A. Langlois, Plattsburgh, N.Y., assignors to Diamond National Corporation, New York, N.Y., a corporation of Delaware

Filed Apr. 27, 1960, Ser. No. 60,336

Term of patent 14 years

(Cl. D44—19)

FIG. 2.

Fig. 1 is a plan view of the cake plate showing our new design; and

Fig. 2 is a vertical section taken along line 2—2 of Fig. 1 and looking in the direction of the arrows.

We claim:

The ornamental design for a cake plate, as shown.
